UNITED STATES PATENT OFFICE.

LOUIS GREENWALD, OF WOODLAWN, PENNSYLVANIA.

UMBRELLA.

1,320,327.

Specification of Letters Patent. Patented Oct. 28, 1919.

Application filed April 23, 1918. Serial No. 230,267.

To all whom it may concern:

Be it known that I, LOUIS GREENWALD, a citizen of Russia, residing at Woodlawn, in the county of Beaver and State of Pennsylvania, have invented certain new and useful Improvements in Umbrellas, of which the following is a specification.

This invention relates to improvements in umbrellas and it is the principal object of 10 the invention to provide a foldable umbrella capable of being folded into compact form when not in use, whereby the same can be conveniently carried or packed, but which, when opened will afford an exceedingly efficient shelter and also will be prevented from unduly collapsing.

Another and equally important object of 20 the invention is to provide an umbrella having novel stays or ribs, which will serve to maintain the same in full open position and also cause the fabric covering thereof to be arranged taut over the same.

Yet another object of the invention is to provide an umbrella having a collapsible 25 stick so constructed as to permit the telescoping of the various sections thereof when it is not desired to use the same.

The invention consists, furthermore, in the novel arrangements and combinations of 30 the parts of the umbrella, as well as in the details of the construction of the same, all of which will be more fully described in the following specification and then finally embodied in the clauses of the claim, which 35 are appended to the specification and which form an essential part of the same.

In the drawings:

Figure 1 is a vertical section through the improved umbrella,

Fig. 2 is a fragmentary section through a portion of the stick thereof,

Fig. 3 is a fragmentary side elevation of the stick,

Fig. 4 is a fragmentary longitudinal section through a portion of the stick and the slidible sleeve,

Fig. 5 is a horizontal section through the stick,

Fig. 6 is a detail in perspective of one of 50 the elements,

Fig. 7 is a detail of the connection between portions of the folding ribs, and

Fig. 8 is a similar view of a connection between other portions of the folding ribs.

Having more particular reference to the drawings, in connection with which like

reference characters will refer to corresponding parts throughout the several views, the stick of my improved umbrella is composed of a plurality of telescopically engaged sections generally indicated by the numeral 1, the inner section which I have designated for the purpose of convenience by the numeral 2 being formed to constitute an effectual handle for the same. Openings 60 3 and notches or seats 4 are formed in the adjacent portions of the sections 1 and are adapted to be alined at times, whereby the off-set end of substantially V-shaped latch elements 5 may be passed therethrough, said 65 elements, obviously, being arranged in the tubular sections and so positioned as to be sequentially engaged by the adjacent inner sections upon the telescoping of the same, in a manner hereinafter more fully described. 70 To prevent relative rotation of the sections, longitudinally disposed key ways 6 are formed in the sections and receive keys in form of screws 7 therein, said screws being carried by annular collars 8 arranged in and 75 secured to said sections 1 in a suitable manner. The inner section 2 is also formed with a longitudinally extending key way 6' for receiving a portion of the screw 7' therein, which as will be noted, is carried by the adjacent portion of the next section 1. In order that the section 2 may be held in distended position with relation to the adjacent section 1, the ordinary form of spring latch 80 9 is arranged in a recess formed therein and 90 as will be understood, is adapted to have the shoulder thereof engaged with the adjacent end of the next section 1. Obviously, by depressing the spring latch 9, the same may be caused to move within the adjacent section 1 by moving the section 2. In this connection, it is to be noted that the section 2 95 is also formed of tubular material, similar to the sections 1.

Fixedly engaged with the upper end of 100 the outermost section 1 is a ferrule 10, while a sleeve 11 is slidably arranged on the intermediate portion thereof and is provided with apertured bearing lugs. To maintain the sleeve 11 in its uppermost position in order that the umbrella can be held open, a spring pressed latch pin 12 is slidably arranged therein and is adapted to be engaged in an opening 13 formed in said outer section 1.

Ribs are provided for the umbrella and include a plurality of crossed pivotally con-

5 nected links 14, certain of which are of less length than the others in order that the usual curve of the umbrella when in open position will be permitted. Stop pins 14' are carried on enlarged ends of some of the links 14 and serve for a purpose hereinafter described. The arrangement of the pivotally connected cross links 14 is such as to constitute the usual lazy tong construction; 10 the inner ends of the ribs being pivotally connected at points about the ferrule 10 as at 15 and to the apertured lugs formed on the sleeve 11 as at 16. Flexible rods 17 are pivotally connected to the outer ends of the 15 ribs as at 18 and have their free ends extended to a point beyond the same whereat they are provided with the usual eyes in order that the fabric covering 19 may be secured to the same. In order that the inner 20 portion or center of the covering 19 can be secured to the stick of the umbrella, a nut 20 is arranged in the upper end of the outer section 1 and is adapted to receive a set screw 21 therein, said set screw having the head of 25 the same bearing on a metal washer 22 which in turn is arranged upon fabric or leather washers 23, these washers having engagement with the adjacent portions of the covering 19 and serving to securely bind the 30 same in position. To render the ribs continuous in order that the covering 19 will be arranged taut thereover, a plurality of links 24 are provided and have their adjacent ends pivotally connected; the outer links being 35 pivotally connected to the adjacent portions of the flexible rods 17 while the inner links are pivotally connected to portions of the ferrule 10 adjacent the connection 15 of certain of the links constituting the ribs 14. 40 Recesses are formed in the ends of the outer links and receive the stop pins 14' therein when in open position to prevent undue movement of said links as clearly shown in Figs. 7 and 8.

45 In using the improved umbrella, to open the same the handle section 2 is engaged and pulled outwardly, thus causing the same and the sections 1 to be moved to their distended positions whereupon the spring latch 9 will 50 engage the adjacent end of the section receiving said handle section 2 and the off-set ends of the latching elements 5 will pass into the seats 4 formed in the adjacent portions of the sections 1 next thereto. In this way, 55 it will be readily understood that the sections constituting the stick of the umbrella will be securely held in their distended or open positions. The sleeve 11 is now grasped and moved upwardly on the outer section 1 60 thus expanding the ribs 14 and causing the

covering to be moved to its open position, whereupon the latch pin 12 is engaged in the opening 13, thus preventing further movement of the sleeve 11. To close the umbrella, it is only necessary to disengage the latch pin 12 from the opening and move the sleeve 11 downwardly on its respective section 1 thus collapsing the ribs 14 and compactly folding the same and the cover 19. At this time, the spring latch 9 is depressed in order that the handle section 2 may be telescoped in the adjacent section 1, whereupon each of said sections are telescoped in sequential order, thus causing the V-shaped latch elements 5 to be sequentially engaged from their respective seats 4 in the various sections 1. Obviously, relative rotation of the sections will be prevented due to the provision of the key ways 6 and 6' and the keys 7 and 7'. Hence, proper functioning of the stick is insured.

Manifestly, the construction shown is capable of considerable modification and such modification as is within the scope of my claims, I consider within the spirit of my invention.

I claim:

1. In a foldable umbrella, a stick, a sleeve slidable on the stick, ribs including a plurality of crossed pivotally connected links having their inner ends pivoted to said stick and sleeve, and flexible frame rods, each including pivotally connected sections pivoted to the outer ends of said links and extending beyond the same.

2. In a foldable umbrella, a telescopic stick, a sleeve slidable on the stick, ribs having links with their inner ends pivoted to said stick and sleeve, flexible frame rods each including pivotally connected sections pivoted to the outer ends of the links and extending beyond the same, and a series of pivotally connected links engaged with the outer ends of said first links adapted to span the space therebetween.

3. In a foldable umbrella, a telescopic stick, a sleeve slidable on the stick, ribs including a plurality of crossed pivotally connected links having their inner ends pivoted to said stick and sleeve, and flexible rods pivoted to the outer ends of the links and extending beyond the same, certain of said links being of greater lengths than the others, and a series of pivotally connected links engaged with the outer ends of said first links, stick and rods and adapted to span the space between said stick and rods.

In testimony whereof, I affix my signature hereto.

LOUIS GREENWALD.
